UNITED STATES PATENT OFFICE

JAMES S. ABERCROMBIE, OF HOUSTON, TEXAS

WHIPSTOCK

Original application filed May 17, 1928, Serial No. 278,414. Divided and this application filed September 10, 1933. Serial No. 632,532.

The invention relates to an improvement in whipstocks employed in sidetracking operations in wells.

When a drill bit has been twisted off or broken in a well or where some other pipe or tools have become lodged in the well bore in such a position that it is impossible or uneconomical to remove them, it is desirable to sidetrack the well bore so that it will be deflected at an inclination and in this manner the bore will pass around the obstruction in the original well bore. With this in mind it is the practice to position a tool or instrument in the well bore closely above the obstruction in such a manner that the drilling of the hole may be resumed, and when the drill bit arrives at the elevation of this whipstock it will be deflected so that it will pass the obstruction below the whipstock.

It is one of the objects of the invention to provide a whipstock which may be positioned in the well bore above the obstruction to deflect the bit so that it will pass the obstruction.

Another object of the invention is to provide a whipstock having an elongated body with an upper cutter deflecting face and a vertical course therethrough, which is adapted for communication with the string of pipe used in positioning the whipstock.

Another object of the invention is to provide a whipstock through which a fluid may be circulated or pumped in positioning the whipstock over the junk or obstruction in the well.

The present application is a division of my earlier co-pending application Serial No. 278,414, for a whipstock, filed May 17, 1928.

The invention will be best understood by having reference to the accompanying drawing wherein Fig. 1 shows a side view of a well bore wherein the whipstock has been positioned above the obstruction and the drill bit is pictured as being deflected by the whipstock to institute the side-tracking operation.

Figs. 2, 3 and 4 are sections taken on the line 2--2, 3--3, and 4--4 respectively of Fig. 1 and showing the configuration of the bit deflecting surface.

The well bore is indicated generally at 1 and this is the original bore which was being drilled with the bit which is pictured at 2. For some reason or other the drill stem 3 connected to the bit 2 has broken as at 4, leaving a portion of the drill stem, the drill collar, and the drill bit in the hole. If such a twist off or break occurs where the upper end 4 is in a soft formation, it is quite liable that the upper end will become embedded in the formation, as pictured in Fig. 1, so that it is practically impossible to remove the obstruction by any form of fishing tool. The obstruction may, however, be any other instrument or tool which has become lost in the well.

The invention is described, however, in connection with a twisted off drill bit, which is a common form of obstruction encountered in the well. Regardless of the type of obstruction, the whipstock 4 will be run into the well by being connected at its upper end at 5 to a suitable string of pipe or drill stem. The upper end 5 of the whipstock is shown as threaded as at 6 to receive the lower end of the string of pipe. The pipe sections are connected end to end so that the whipstock is lowered into the well. There is a passage 10 provided through the whipstock, through the thread 6, and which passage terminates in the openings 11 at the lower end 7 of the whipstock. This passage is provided so that circulation may be maintained while the whipstock is being lowered into position and thus prevent freezing of the flushing fluid in the well bore as well as to wash away any cavings or sediment which has lodged directly above the junk or obstruction in the well. Various methods are followed in orienting the whipstock so that the continuation of the well bore will be in the desired direction.

After the whipstock has been positioned the string of pipe may be disconnected from the threads 6 and removed from the well. If the whipstock is cemented in position the cement is allowed to set and then the drill bit 15 is run into the well until it strikes the bit deflecting surface 16 on the whipstock. The peculiar construction of the bit deflecting

surface is disclosed in the parent application of which the present application is a division.

What I claim as new is:

1. A whipstock, comprising an elongated body having a cutter deflecting upper face, and having a vertical course therethrough adapted for communication with a string of pipe.
2. A whipstock for wells including a body, 10 a connection on the upper end thereof for an operative string of pipe, and a passage thru said body whereby fluid may be passed from the operative string of pipe thru said body.
3. A whipstock for sidetracking well bores 15 including a threaded connection on the upper end thereof, adapted to receive a string of pipe for setting the whipstock, a passage extending from said connection adapted to allow fluid to be passed from the setting string 20 of pipe into said whipstock.
4. A whipstock thru which circulation may be had including a body, said body having a passage longitudinally thereof, and means for connecting a pipe to said whipstock 25 whereby fluid may be passed therewith.

In testimony whereof I hereunto affix my signature this 10 day of August, A. D. 1932.

JAMES S. ABERCROMBIE.
